UNITED STATES PATENT OFFICE.

FREDERICK DARLINGTON, OF PITTSBURG, PENNSYLVANIA, ASSIGNOR TO WESTINGHOUSE ELECTRIC & MANUFACTURING COMPANY, A CORPORATION OF PENNSYLVANIA.

VOLTAGE-REGULATOR.

No. 920,925.

Specification of Letters Patent.

Patented May 11, 1909.

Application filed March 3, 1906. Serial No. 304,064.

To all whom it may concern:

Be it known that I, FREDERICK DARLINGTON, a citizen of the United States, and a resident of Pittsburg, in the county of Allegheny and State of Pennsylvania, have invented a new and useful improvement in Voltage-Regulators, of which the following is a specification.

My invention relates to voltage regulators and particularly to regulators of the class in which voltage variations are effected by varying the active lengths of transformer windings.

One object of my invention is to provide a novel and improved structure and arrangement of parts of a regulator of the above specified class, whereby voltage variation may be effected in circuits that are traversed by large amounts of current without injury to the regulator parts.

A further object of my invention is to provide an improved means and a system for controlling the operation of voltage regulators.

Figure 1 of the accompanying drawings illustrates diagrammatically, a system embodying my invention and Fig. 2 is an enlarged view, in side elevation, of a portion of the regulator shown in Fig. 1.

Alternating current energy may be supplied from a trolley conductor 1 and a track rail 2, through a lowering transformer 3, or otherwise, to a voltage regulator 4, that comprises a magnetizable core 5 and two windings 6 and 7. The corresponding terminals of the two windings are connected together by means of resistances 8 and 9, respectively, to which circuit connections are made at the middle or other points intermediate the terminals thereof. For more successful operation, the windings 6 and 7 should be intercoiled or juxtaposed upon the same portion or portions of the magnetizable core 5, and, as here illustrated, are preferably composed of strap or bar conductors that are intercoiled upon one leg of the core structure in such a manner that the outer, exposed faces of the respective windings alternate with each other in a manner similar to that in which the threads of a double threaded screw are disposed.

The windings are also provided, preferably, with flat faces to be engaged by a movable contact member 10 that may be operated by any suitable means, such as a

screw 11, the contact member 10 being connected to a translating device 10^a which is to be supplied with variable voltages. The structure of the movable terminal member constitutes the subject-matter of another application, Serial No. 304,065, filed by me of even date herewith and comprises a frame 12, a shaft 13 having bearings therein, a plurality of contact rings 14 and 15 that differ slightly in diameter and are resiliently but securely mounted upon the shaft 13 by any suitable means, such as springs 16, so that all of them will rotate at the same speed. When so constructed, a large degree of contact pressure may be exerted by the device 10 without causing an undue amount of friction, while the contact surfaces will be maintained clean by the rubbing action of the rings 14 and 15 upon the engaging surfaces that results from the difference in the diameters of the contact rings, the amount of such rubbing action being insufficient, however, to effect excessive wear of the engaging surfaces.

The screw 11 may be operated, through intermediate gearing 17, by a motor 18, one terminal of the armature 19 of which is connected to a brush 20 that is carried by, but insulated from, the frame 12 of the movable member 10 and is adapted to engage the exposed faces of the windings 6 and 7. The brush 20 is so arranged that it never becomes disengaged from the windings 6 and 7 even though the movable member 10 does become disengaged. The other terminal of the armature 19 is connected to the middle or some other point intermediate the terminals of the field magnet winding 21 of the motor, the terminals of which are connected, respectively, to contact terminals 22 and 23 with either of which the switch arm 24, of a reversing switch 25, is adapted to engage.

The reversing switch, which constitutes the subject-matter of a divisional application, filed October 20, 1908, Serial No. 458,616 comprises, further, a ratchet segment 26 which carries the switch arm 24 and a pawl 27 that is actuated by the operating lever 28 of a master controller 29. The pawl 27, as here shown, is provided with a piston that is yieldingly held in operating position by a spring 30 in a frame or cylinder 31, the latter being resiliently connected to the switch lever 28 by a spring 32 that normally tends to maintain the pawl parallel with the 110

lever. In order to explain the operation of the reversing switch, it may be supposed that the switch lever 28 is moved to the left, and that the pawl 27 is thereby caused to engage 5 the ratchet 26. The reversing switch arm 24 is first moved into engagement with contact terminal 23 and against a stop 34 and, as the motion of the lever 28 to the left continues, the pawl 27 is pressed into the cylinder 31 against the spring 30 until it passes the center line of the switch lever 28, when it is again pressed outwardly and trails behind the lever. If the lever 28 is moved to the right, from the position shown, the pawl 15 simply trails behind it over the ratchet, but if the pawl occupies a position on the opposite side of the lever it will engage the ratchet and cause the reversing switch arm to be moved into engagement with contact terminal 22 and against a stop 33. It will thus be understood that, upon reversing the direction of the motion of the switch lever 28, the pawl 27 is caused to engage the ratchet 20 26 and effect operation of the reversing switch 25.

The master controller 29 comprises a plurality of conducting segments 35, 36, 37, 38, 39, 40, 41 and 42 that are connected, respectively, to suitable points of an auxiliary 30 transformer winding 43 or with any other suitable source of variable voltages. The voltage steps of the master controller, correspond to predetermined voltage that may be derived from the regulator 4 in order that, 35 in the operation of the system, a voltage shall be applied to the motor 18, when the movable terminal member 10 and the switch lever 28 occupy non-corresponding positions, that is, when the terminals with which they 40 engage are supplied with different voltages. For example, if the switch lever 28 is moved, from the position shown, into engagement with conducting segment 41, a circuit will be established from a point 44 in the auxiliary 45 transformer winding 43, through conducting segment 41, switch lever 28, reversing switch lever 24, contact terminal 22, one-half of field magnet winding 21, armature 19, brush 20, and a greater or less portion of the 50 regulator windings 6 and 7, according to the position of the member 10. The voltage applied to the motor 18 will then be equal to the difference of potential existing between the contact terminals 39 and 41 of the master 55 controller 29, and this voltage will be gradually decreased until the movable terminal member 10 engages the regulator windings at such a point that the voltage applied to the movable terminal 10 will equal that of 60 the conducting segment 41. If the switch lever 28 is moved in the opposite direction, the reversing switch 25 will first be operated so as to bring the arm 24 into engagement with the contact terminal 23, whereupon the 65 other section of the field magnet winding will

be introduced into the circuit, thereby reversing the direction of rotation of the motor and consequently the direction of movement of the contact member 10.

It will be observed that the contact rings 70 14 and 15 of the movable terminal 10, first engage one of the regulator windings, next both of them and then the other. When they engage both of the windings, local closed circuits are established but the voltages of these circuits will be low because the differences of potential applied to the respective portions of the windings that are included in the closed circuits will be equal to only that applied to a half turn of the winding. The amount of current that will traverse these circuits will also be limited by the resistances 8 and 9. When the contact rings 75 14 and 15 engage but one of the windings, only a half of each of the resistances 8 and 9 is included in circuit, the resistance losses in the regulator being in this manner reduced. It will, of course, be understood that special resistances 8 and 9 may be employed or that the leads to the regulator 80 windings may be extended sufficiently to introduce the proper amount of resistance into the circuit.

In order to obviate serious sparking and burning of the contacts when the movable member 10 becomes disengaged from the regulator windings at the low potential end of the regulator, I have provided a specially constructed terminal member comprising a plurality of sections 45, 46, etc. that are composed, alternately, of carbon or other high resistance material and of low resistance material such as copper, or of the material of which the regulator windings are composed, and that are placed adjacent to the last contact surface 47 of the regulator. The carbon serves to introduce resistance into the circuit and to thereby reduce the amount of current traversing it, and the intervening sections of copper or other low resistance conducting material serve to prevent a high current density near the contact surface of the terminal by conducting the current from the portions of the carbon that are remote from the contact surface. When the amount of current 100 is sufficiently reduced by these means, the contact rings 14 and 15 engage an insulating section 48, whereupon operation of the regulator ceases.

Although I have shown the regulator as 105 comprising windings that are provided with exposed faces with which the movable terminal member may engage, it will be readily understood that, if desired, the windings may be connected to suitable contact terminals with which the movable terminal may engage, and also that the windings may be disposed in any other suitable manner on the magnetizable core with due regard to the 110 fact that they should be placed as closely 115 120 125 130

together as possible upon the same portion or portions of the core. The operating motor for the regulator may be of any other suitable form, that here shown being selected 5 because of the small number of conductors necessary to effect its control and the resultant adaptability to the control of a plurality of motor-operated cars in a train, it being necessary to extend from car to car only conductors 49 and 50.

The structural details of the parts and the arrangement of the circuits are subject to variations within considerable limits without altering the mode of operation of the invention or departing from its spirit and I desire that all such modifications be included within its scope.

I claim as my invention:

1. The combination with a transformer having a plurality of windings severally provided with a series of contact terminals that alternate with each other, a movable terminal adapted to successively engage said contact terminals, and a motor for governing the position of the movable terminal, of another set of contact terminals, means for supplying them with different voltages, and a switch arm to engage said contact terminals for governing the motor circuits.
2. In a voltage regulator, the combination with a transformer having a plurality of juxtaposed windings arranged in parallel circuit and means for making circuit connections alternately to successive points in said windings.
3. In a voltage regulator, the combination with a transformer having juxtaposed windings arranged in parallel circuit and means

for making circuit connections alternately to the respective windings.

4. The combination with a translating device and a voltage regulator comprising juxtaposed transformer windings arranged in parallel circuit, of means for connecting one terminal of the translating device alternately 45 to the one or the other of the transformer windings and to both windings.

5. A pair of relatively movable engaging circuit terminals one of which comprises a main, low-resistance conducting portion and 50 alternate conducting portions of high and low resistance, respectively.

6. A pair of relatively movable engaging circuit terminals one of which comprises a main, low-resistance conducting portion and 55 alternate portions composed of metal and carbon, respectively.

7. The combination with a set of circuit terminals to which variable voltages are applied, the terminal at one end of the set comprising a main, low-resistance conducting portion and alternate conducting portions of 60 high and low resistance, respectively.

8. The combination with a set of circuit terminals to which variable voltages are applied, the terminal at one end of the set comprising a main low-resistance conducting portion and alternate conducting portions composed of metal and carbon, respectively.

In testimony whereof, I have hereunto 70 subscribed my name this 21st day of February 1906.
